HORSE SHOE GAME SCORING DEVICE

Frank E. Plush, 7161 Chestnut Drive,
Walton Hills, Ohio 44146

Filed July 25, 1972, Ser. No. 274,916

Term of patent 14 years

Int. Cl. D21—01
U.S. Cl. D34—5 MM

FIG. 1 is a top plan view of my novel horse shoe game scoring device;

FIG. 2 is an edge view thereof;

FIG. 3 is an end view thereof; and

FIG. 4 is a longitudinal sectional view thereof taken substantially on line 4—4 of FIG. 1.

I claim:

The ornamental design for a horse shoe game scoring device, substantially as shown and described.
